UNITED STATES PATENT OFFICE.

JOHANNES TH. PEDERSEN, OF NEW YORK, N. Y.

DESIGN FOR A TOOL-HANDLE.

SPECIFICATION forming part of Design No. 20,358, dated December 2, 1890.

Application filed November 3, 1890. Serial No. 370,232. Term of patent 7 years.

To all whom it may concern:

Be it known that I, JOHANNES THEODOR PEDERSEN, a citizen of the United States, residing at the city, county, and State of New York, have invented and produced a new and original Design for Tool-Handles, of which the following is a specification, reference being had to the accompanying drawings, forming part thereof, in which—

10 Figure 1 is an elevation showing my design, and Fig. 2 is an end view of the same.

The leading feature of my design for a tool-handle is the oblique or diagonal flutes or grooves in the surface of the round handle.

15 The portion B of the handle usually is tapering.

The design of the handle relates to the parallel, oblique, or inclined flutes or grooves D in the round and nearly cylindrical part A, as shown, and such flutes are nearly semicircular and the end of the handle convex, as shown at C.

What I claim is—

The design of the tool-handle, substantially as described and represented.

Signed by me this 29th day of October, A. D. 1890.

JOHANNES TH. PEDERSEN.
